UNITED STATES PATENT OFFICE.

JOHN J. GARDNER, OF LANCASTER, INDIANA.

PUMP.

SPECIFICATION forming part of Letters Patent No. 241,856, dated May 24, 1881.

Application filed September 4, 1880. (No model.)

To all whom it may concern:

Be it known that I, JOHN J. GARDNER, of Lancaster, in the county of Jefferson and State of Indiana, have invented a new and valuable improvement in Pumps; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a central vertical section of this invention. Fig. 2 is a transverse section. Fig. 3 is an exterior view, showing the agitating device. Figs. 4, 5, and 6 are details.

This invention has relation to single-acting pumps; and it consists in the construction and novel arrangement of the four tapering edge lapped boards forming the barrel, the valved tube let into the lower end of the same, the loose valve-block and slotted rubber cap extending beyond its sides, and the perforated blocks secured to a reciprocating rod arranged in ways on the outside of the pump-barrel, all as hereinafter shown and described.

In the accompanying drawings, the letter A designates the pump-barrel, which is constructed of four boards of the same size and shape, each board *a* being tapering slightly and usually about ten feet long, being one-eighth of an inch wider at the top than at the bottom. These boards are put together in such a manner that each board has one edge, *b*,lapping the next on one side, while on the other side its other edge, *c*, is abutting against the edge of the adjacent board, so that there is one seam only on each side of the barrel, which has a square aperture, *d*, the top of which is one-eighth of an inch wider than the bottom portion.

Into the lower end of the barrel is inserted and secured a pipe or tube, B, squared to fit the chamber, and having an end piece, *e*, and inlet-openings *f* on each side. To the top of this pipe or tube B, which forms the valve-seat *g*, is fitted a valve, C, consisting of a flat piece of rubber, *h*, having a block, *k*, nailed thereto, the rubber being nailed by one edge to the valve-seat, thereby forming the check-valve of the pump.

The plunger D consists of a square block, I, cut of smaller diameter than the aperture of the barrel, so as to fit within it loosely, leaving a space between its sides and the barrel-wall. A tenon, *l*, is formed on the upper end of the valve-block, projecting upward centrally between the corner holes, *m*, which are made through the block for the passage of the water. 55

A square rubber cap, *n*, of flat or sheet rubber is cut of sufficient size to fit the aperture of the barrel closely, and is formed with a central cross-cut, *s*, so that it can be pushed down over the tenon *l*, and will then be square with its seat on the upper surface of the valve-block 60 I, beyond the sides of which it extends, as shown in the drawings. This cap, being elastic, clasps the tenon, and the angular inside flaps *p* are nailed to the tenon. The edges of the rubber cap are designed to make an air-tight joint with the inside wall of the barrel, 65 which is rendered closer in the lower part of the barrel because of its taper.

The tenon *l* of the valve-block forms a part of the plunger-stem E, to which it is rigidly 70 connected by halving and bolting, as shown at *r*.

Around the barrel, at its bottom, a metallic strap, F, is secured, holding the component boards *a* together more securely in this part, 80 while at the top tie-strips *t* are nailed around on three sides, as shown, said strips connecting on the fourth side with the lever-support G, which is nailed to the side of the barrel, and is provided with a forked branch, H, which 85 projects above it.

L represents the lever, which is pivoted to said support, and is connected to the plunger-stem by means of a hook-hinge, *v*. To the outer arm of this lever is pivoted the jointed or flexible end J of a reciprocating-stem, K, which works in bearings *w*, secured to the barrel-wall, and which is provided with upper and lower agitating heads or blocks, U V, which are perforated at *z*, and which are moved up and down 90 in the water, outside the pump-barrel, when the plunger-lever is operated, and serve to create currents in the water about the inlet-openings in the entrance-tube B, and to prevent stagnation. 95

z represents the spout, secured in a board of the barrel, near its upper end. 100

The operation of the pump is as follows: The barrel being tapering from top to bottom, the plunger descends and the space between the sides of the block I and the walls of the pump-barrel gradually lessens as the plunger approaches the bottom. The rubber cap *n*, having its edges extended beyond the sides of the block I, is in contact with the walls of the barrel, and is lifted by them and the water during its descent. The water passes through the holes *m* and around the sides of the block I, and passes the edges of the rubber cap *n*. When the plunger has reached the end of the downward stroke the upward stroke commences, and, owing to the tapering form of the barrel, the rubber cap *n* packs the barrel so tightly at this point that no leakage of the water above the cap can take place; hence a greater volume of water is lifted than would be were the barrel straight throughout. The rubber cap *n* will not rot, as does leather, and taint the water after long use. The block I being smaller than the inner area of the barrel, no friction has to be overcome, except that of the rubber cap *n*, and this is so slight as not to wear the barrel; and when the cap itself becomes worn it can be replaced by any ordinary mechanic.

The operation of the agitator has already been explained.

Agitators for stirring the water to prevent stagnation are not broadly new, and are not so claimed herein. A wire secured to the pump-rod, and having disks attached to it, has been used for this purpose; and a rod has been con-

nected to the pump-handle and provided with a perforated stirrer or agitator at the bottom; but in both these instances no guides are used, nor are the agitators connected in any way to the pump-barrel below the water, as in my invention. By the employment of the guides the agitator will not be deflected by the water, and the action of the pump is made certain.

Having described this invention, what I claim, and desire to secure by Letters Patent, is—

1. In a pump, the barrel A, formed of four tapering boards, *a*, the face of each of which is lapped over the edge of the next, thereby forming a single seam in each side of the barrel, as set forth.

2. The combination of the valve *n*, cut, as shown at *s*, to form flaps *p*, with the plunger-block I, stem *l* E, tapering barrel A, and check-valve C, substantially as and for the purposes set forth.

3. In a pump, the combination, with the lever L and pump-barrel A, of the reciprocating stem K, working in bearings *w*, and provided with the agitating blocks or heads U V *z*, substantially as and for the purposes set forth.

In testimony that I claim the above I have hereunto subscribed my name in the presence of two witnesses.

JOHN J. GARDNER.
